Primary Examiner — Karen S Acker

(74) Attorney, Agent, or Firm — BURR & FORMAN LLP

(57) **CLAIM**

The ornamental design for a nonwoven fabric, as shown and described.

DESCRIPTION

FIG. 1 is front perspective view of a nonwoven fabric, embodying the new design;

FIG. 2 is plan front view of the nonwoven fabric of FIG. 1; FIG. 3 is a right-side view of the nonwoven fabric of FIG. 1;

FIG. 4 is a left-side view of the nonwoven fabric of FIG. 1; FIG. 5 is a top-side view of the nonwoven fabric of FIG. 1; FIG. 6 is a bottom-side view of the nonwoven fabric of FIG. 1; and,

FIG. 7 is plan rear view of the nonwoven fabric of FIG. 1. The broken lines in the figures represent portions of the nonwoven fabric that form no part of the claimed design.
